VOLTAGE ATTENUATOR

William R. Hewlett, Palo Alto, Calif., assignor, by
mesne assignments, to Hewlett-Packard Company,
Palo Alto, Calif., a corporation of California

Application June 29, 1946, Serial No. 680,368

2 Claims. (Cl. 178—44)

1

This invention relates generally to attenuators such as are employed for developing a predetermined voltage less than a known applied voltage.

In the past voltage attenuators used in connection with signal generators or other high frequency electronic equipment have been primarily of three general types, namely resistance, mutual inductance, and mutual capacitance. The resistance type of attenuator consists generally of a network of the ladder type with available points of connection to give voltage attenuation in uniform steps. The mutual inductance type of attenuator makes use of input and pickup coils mounted within a conductive shielding tube, and adjustable axially along the tube to vary the mutual inductance. In attenuators of the mutual capacity type two electrostatic condenser electrodes are employed which are adjustable with respect to the spacing or distance between them, to provide a desired degree of attenuation.

The three types of voltage attenuators described above, and other miscellaneous attenuators which have been available in the past, have been subject to certain limitations and disadvantages. In general such attenuators are subject to large variations in input and output impedances with frequency, or do not afford a relatively high degree of accuracy over a wide frequency range of say from 1 kilocycle to 800 megacycles. This latter deficiency is due to a variety of factors including the presence of unpredictable errors which interfere with the desired accuracy. For example with attenuators of the resistance type errors can be attributed to stray capacity coupling between the various sections of the ladder, the effect of which is particularly noticeable for the higher frequencies.

It is an object of the present invention to provide a voltage attenuator of the resistance type which will afford a relatively high degree of accuracy for the step by step attenuation, with retention of this accuracy over a wide frequency range.

A further object of the invention is to provide a resistance type of attenuator utilizing a ladder network which will not be subject to unpredictable errors due to stray capacity coupling between the elements of the network and with relatively constant input and output impedances.

Additional objects of the invention will appear from the following description in which the preferred embodiment has been set forth in detail in conjunction with the accompanying drawing.

Referring to the drawing:

Figure 1 is a side elevational view in section

2

illustrating an attenuator incorporating the present invention.

Figure 2 is a cross sectional view taken along the line 2—2 of Figure 1.

5 Figure 3 is a circuit diagram serving to illustrate the ladder network formed by the resistance element of my attenuator.

The attenuator illustrated in the drawing consists of a hollow conducting tube 10 formed of 10 suitable metal such as brass or copper, and which is preferably circular in cross section. Aligned with and spaced longitudinally along the axis of the tube are the contact elements 11. These elements are preferably in the form of conducting 15 rings made of suitable metal, and provided with annularly disposed spring contactor brushes 12, for a purpose to be presently described. In manufacture these brushes can be formed integral with a thin sheet metal spring annulus 13, which 20 is attached as by soldering to one face of the contactor body. At the input end of the attenuator a cup-like contactor element 14 is provided, and which carries the axial stud conductor 16. The corresponding end of the tube 10 is provided with 25 a metal closure 17, which has a central aperture 18 to receive one end of a coaxial transmission line. The central conductor of the transmission line can make direct connection with the stud conductor 16.

30 A plurality of conducting rings 19 surround the contact elements 11 and are dimensioned to loosely fit within the tube 10. Split metal spacer rings 21 are interposed between the rings 19, and are normally sprung outwardly to have frictional and electrical contact with the tube 10. They 35 serve to insure grounding of rings 19 to tube 10 and to maintain accurate spacing along the length of the device.

40 A plurality of resistors 23 of proper value connect between the contact elements 11 and the conducting rings 19. Preferably these resistors are distributed symmetrically about the axis of the attenuator, and for example three such resistors displaced 120° apart can be used with each 45 contact element 11. Additional resistors 26 connect between the successive contactor elements 11. These resistors are likewise symmetrically distributed and assuming that three such resistors are employed as in the case of the resistors 50 23, the distribution can be as illustrated in Figure 2. It is convenient to utilize resistors having a fair degree of mechanical strength with relatively rigid extending terminal wires. Soldering of such terminal wires to the contactor elements 11 and the outer rings for the resistors 23, and to

the successive contactor elements for the resistors 26, affords a structure of considerable mechanical strength sufficient to retain the contactor elements 11 in proper position along the axis of the device.

The output end of the attenuator is provided with a metal closure 28 having a central opening 29. The inner face of this closure is recessed to seat the last one of the series of contactor elements 11 as illustrated. Opening 29 serves to accommodate a probe 31 which can be inserted into the attenuator for the purpose of making electrical connection with a selected one of the contactor elements 11. The probe illustrated consists of an outer conductor sleeve 32, within which is an axial conductor 33. At the inner end of the probe the sleeve 32 is provided with an insulator 34, through which the adjacent end of the conductor 33 extends. The projecting end of the conductor 33 carries a contacting element 36 in the form of an enlarged metal head which is circular in transverse cross section, and which is dimensioned for good electrical connection with the resilient brushes 12 of the contactor elements 11.

The probe is of sufficient length whereby the contactor element 36 can be inserted to make engagement with any one of the contactor elements 11 or the input contactor element 14. The inner end of the sleeve 32 is also proportioned to make electrical engagement with all of the contactor elements 11 on the output side of that element which is connected to the central conductor of the probe. The outer end of the probe is coupled to a suitable coaxial transmission line 37 which has its outer hollow conductor grounded, whereby the sleeve 32 of the probe and the tube 10 of the attenuator are likewise grounded. Thus sections of the ladder network which are on the output side of the last section being contacted by the probe are grounded out, thus avoiding possible intermediate errors.

The ladder type network formed by the construction described above is illustrated diagrammatically in Figure 3. The resistors 23 are considered as grouped to form the resistance elements R_1 , and the resistors 26 are grouped to form the resistance elements R_2 . Conductor 10a is representative of the tube 10, which is grounded together with the sleeve 32a (representing the probe sleeve 32).

The attenuator can also be constructed of resistors having uniformly distributed constants such as disc resistors and resistive tubes. By proper choice of dimensions, it is possible to construct this attenuator of uniformly distributed resistors so that for all elements, both series and shunt

$$\rho/t = \text{a constant}$$

where

ρ =the resistivity of the resistance material
 t =thickness of resistance material.

It would thus be possible to construct this attenuator by initially assembling the supports for the resistors only, and then coating these supports uniformly to the required thickness with some resistive material.

A feature of my attenuator is that the effective inner diameter of the tube 10 (i. e., the inner diameter of split rings 21) and the length between each section of the ladder are so proportioned and selected that the attenuation suffered by stray capacity coupling between sections, including the coupling between successive contact elements 11,

is made substantially greater than the step by step attenuation of the ladder network. This makes it possible to reduce errors due to stray capacity coupling to relatively low and insignificant values. I have found that insofar as capacity coupling between the ladder sections is concerned, the cylindrical tube 10 acts as a wave guide below cut-off frequency. Therefore the attenuation of stray capacity coupling can be calculated on the basis of known wave guide theory. Thus per inch lineal distance along the length of the tube the stray capacity coupling suffers an attenuation in db. (decibels) which can be expressed by an equation as follows:

$$\alpha = 8.68 \times \frac{2\pi}{\lambda c} \sqrt{1 - \left(\frac{\lambda c^2}{\lambda}\right)}$$

where

λc is the cut off wave length in inches for the TM_{01} mode.

λ is the wavelength in inches of the signal applied.

Assuming that

$$\lambda >> \lambda c$$

then

$$\alpha = 8.68 \frac{2\pi}{\lambda c} \text{ db./in.}$$

Since the mode TM_{01} furnishes the unwanted coupling

$$\lambda c = \frac{2\pi a}{2.4}$$

where a is the tube 10 radius in inches
therefore

$$\alpha = 8.68 \times \frac{2.4}{a} \text{ db./in.}$$

$$= \frac{20.9}{a} \text{ db./in.}$$

Assuming that the ladder network is such that each section has of itself an attenuation of α_a , then the length of each section, l , should be such that

$$\frac{20.9l}{a} > \alpha_a$$

Assuming that Z is the desired output impedance of the attenuator, Z_0 is the necessary source impedance of the generator feeding the attenuator, and γ is the reduction of voltage per section, then

$$R_1 = \frac{Z}{(1-\gamma)^2}$$

$$R_2 = \frac{Z}{\gamma}$$

$$Z_0 = \frac{Z}{1-\gamma}$$

In practice it is desirable to construct the attenuator in such a manner that the attenuation is in uniform steps, for example 10 db. for each section. The coaxial probe should be designed so that its characteristic impedance is the same as the desired output impedance.

One attenuator which has been constructed in accordance with the foregoing used groups of three resistors is illustrated in the drawing. The attenuation for each step was 10 db. and the output impedance was 50 ohms. For the frequencies of 1 kc., 30 mc., 300 mc., 500 mc. and 800 mc., the attenuation was substantially that cal-

culated. Looking back into the output the voltage standing wave ratio was less than 1.2 for all frequencies below 800 Mc. when measured with a generator having a source of impedance of 50 ohms.

It will be evident that the invention can be modified in various ways within the scope of the invention. The number of resistors forming each element of the network can be varied, or if desired resistors having uniformly distributed constants can be used, such as disc resistors and resistive tubes.

I claim:

1. In a voltage attenuator for use with high frequency electrical equipment, a hollow conducting tube, a plurality of conducting rings disposed axially within the tube and spaced longitudinally of the same, a plurality of resistors disposed within the tube and connected to form with said tube an attenuating network of the ladder type, said network including resistors connected between adjacent conducting rings and resistors connecting between the resistor rings and the conducting tube, said network providing step-by-step voltage attenuation for selective connections to said conductor rings, means for applying a voltage input to one end of the network at one end of the tube, and means including a probe adapted to be slidably inserted into the other end of the tube and through said conducting rings for making selective connection with a selected one of said rings to thereby provide an attenuated output.

2. In a voltage attenuator for use with high frequency electrical equipment, a hollow conducting tube, a plurality of conducting rings disposed axially within the tube and spaced longitudinally

of the same, a plurality of resistors disposed within the tube, certain of said resistors being connected between adjacent rings and spaced circumferentially with respect to each other, other of said resistors being spaced circumferentially and extending radially from each ring to the adjacent portion of the surrounding tube, said resistors together with said tube and said conducting rings forming a resistive attenuating network of the ladder type providing step-by-step voltage attenuation for selective connections to said conductor rings, means for applying a voltage input to one end of the network at one end of the tube, and means forming a coaxial probe slidably inserted in the other end of the tube, said probe comprising a shield tube and an inner conductor disposed axially of the shield tube and provided with an enlarged metal head disposed beyond the end of the shield tube, said head serving to make electrical contact with a selected conductor ring, said shield tube serving to contact and ground the remainder of the conductor rings intervening between the selected ring and the output end of the first mentioned tube.
